UNITED STATES PATENT OFFICE

2,147,491

SIDE TRACKER FOR OIL WELL EQUIPMENT

George F. Le Bus, Longview, Tex.

Application December 4, 1936, Serial No. 114,140

1 Claim. (Cl. 64—7)

This invention relates to well boring equipment and particularly to improvements in such equipment for avoiding obstructions such as tools lost in the hole, broken drill bits, and the like.

5 The primary object of the invention is to provide a means for continuing the drilling operations without removing such obstructions by the ordinary fishing tool method and by side-tracking the obstruction by the drilling of a pocket to one side of the well bore and removing the object into the pocket and then continuing the drilling operations in the path of the vertical well bore.

Another object of the invention is the novel 15 construction of the side-tracking device and wherein the latter is adapted to be moved laterally within the circumference of a circle and made to bore an angular side-track pocket at any desired point in a line with said circumference.

20 The above principal and other important objects of the invention will be more clearly understood by a perusal of the following detailed description, taken in connection with the accompanying drawing, and in said drawing:

25 Figure 1 is a sectional representation of a well bore and a section of drill pipe with the side-tracking device embodied therein, the latter being shown in a side-track boring position.

Figure 2 is a longitudinal, sectional detail view 30 of the central part of the side-tracking device, showing the means of connecting the upper and lower parts by means of a ball and socket construction, the side-tracking element being shown in a non-side-tracking position.

35 Figure 3 is a view similar to Figure 2, but illustrating the side-tracking element in a side-track boring or boring position and showing a flexible water hose, and means for connecting the hose in position in the water line.

40 Figure 4 is a cross-sectional view of Figure 2, the view being taken on the line 4—4 thereof.

Figure 5 is a sectional detail view of the ball supporting part for the side-tracking element, the latter being removed, and

45 Figure 6 is an elevational view of one of the rollers associated with the ball and ball supporting part.

Referring more in detail to the drawing, 1 represents a well bore made in the earth 2 in the usual manner, the broken lines 3 indicating the continuation of the bore after the obstruction, as of a broken drill bit 4, has been side-tracked or diverted from the vertical bore of the well. The device is connected to a string of drill pipe as at 5 by means of a short length of

pipe 6 having a tool-engaging surface 7. The lower end of the pipe 6 is then connected to the end 8 of the upper portion of the device. The side-tracking parts comprise the tubular element 9, the ball retaining element 10, the ball 11 on its stem 12 and the rollers 13.

The construction which permits a lateral or angular position from the true vertical bore of the hole being drilled is carried out by the arrangement of the ball 11 and the ball retaining element 10, the latter having formed therein a socket 14—see Figure 5. The socket 14 is formed by the curved or rounded surface 9a of the lower end of the tubular element 9, threadedly engaged at 9b with the ball retaining element 10, the formation also being carried out by the curved and rounded surface 10a of the ball retaining element 10. The rounded surface of the tubular element 9 while constituting part of the socket also provides a means for holding the ball in 20 position. The socket thus formed is continuous with the bore 9c in the element 9 and with the diverging or flared bore 10b in the element 10. The stem 12 is adapted to receive a drill bit 16 for drilling the side-pocket A.

In assembling the parts, the nipple 20, with the flexible element 17, is inserted in the upper end of the hollow body 9 by a suitable tool. The flexible element is then secured at its opposite end to the ball projecting means 19. The rollers 30 are then set in the recesses in the sleeve and the ball and stem element moved into engagement with the rollers. The sleeve is then screwed into engagement with the reduced portion of the hollow body 9.

Means are provided for directing a continuous flow of water pressure to the drill bit when the ball and stem are in an angular side-track boring position by the flexible hose 17. The stem 12 and ball 11 are channeled or bored at 18 and the ball 11 has formed thereon a conical projection 19. The hose 17 is connected to the projection 19 and then secured to a nipple 20, the latter being threaded into the tubular element 9 as shown in Figure 3.

One of the important features of the side-tracking device is the means for holding the stem and ball in an angular position such as shown and for simultaneously rotating the same on its axis to operate the bit 16. This is accomplished by the rollers 13 and the ball 11. The ball retaining element 10 has spaced recesses 21, larger than the rollers 13 in order to provide ample free movement of the rollers in these recesses. The ball 11 is also provided with similar recesses 22.

- This construction provides in effect a universal joint. When the ball and its stem are vertically positioned as in Figure 2, these recesses are in alignment, but when the stem is moved to a diagonal position as in Figures 1 and 3, the reduced portion 12a of the stem abuts the wall of the flared opening 10b, causing the rollers 13 to occupy the positions shown in Figure 3. That is, the rollers 13 are then at the top of the recess 21
- 10 on one side of the element 10 and at the bottom of recess 21 on the opposite side of the element. Likewise the inner ends of the rollers 13 occupy similar positions in the ball 10. This arrangement enables the stem 12 with the drill bit 16 to
- 15 rotate on its axis and drill a side pocket to the side of the vertical bore.

- In the operation of the device and in case a drill bit 4 is lodged in the bottom of the hole as shown in Figure 1, the side-tracking device is attached to the drill stem and lowered into the well. As the bit 16 comes in contact with the obstruction 4 and the drill stem and bit rotated the bit will slip off the obstructing object and bore a side-tracking hole A of sufficient depth to
- 20 remove the broken bit out of the vertical bore. The side-tracking device is then withdrawn to the surface and the regular drill bit placed on the drill stem, as in drilling a vertical bore in the regular way. As the bit is lowered it strikes the broken bit and kicks and shoves it to one side into the pocket A and the boring is continued as indicated by the broken lines 3.

- While the construction shown embodies the principle of the invention, it is to be understood that changes and modifications may be made therein, in keeping with the intent of the device

and within the scope and meaning of the appended claim.

What is claimed is:

A side-tracking device for well boring comprising a tubular body, a hollow body threadedly engaged therewith, the hollow body having a reduced portion, a sleeve element threadedly engaged with the said reduced portion of the hollow body, a socket formed in the reduced portion of the hollow body and the said sleeve element, a ball and stem element, the ball of the ball and stem element being disposed in said socket, and the ball and stem element having a bore extending longitudinally thereof, said ball portion of said ball and stem element and said socket having a plurality of annularly spaced recesses, a plurality of roller elements in said recesses, said recesses being sufficiently dimensioned to permit the rollers to move freely therein without binding, buckling or interfering with the movement of the said ball and stem element, said sleeve being provided with flared and outwardly diverging walls, and the stem of the ball and stem element having a reduced upper portion adjacent the outwardly diverging walls of the sleeve element to permit the ball and stem element to move angularly with respect to the vertical position of the tubular body, the hollow body having a bore in one end, a nipple secured in the said bore, a bored projection on said ball of the ball and stem element and communicating with the bore in the said ball and stem element, and a flexible element connecting said ball with said nipple.
